IDENTIFICATION DEVICE OR MARKER FOR COOPERATING WITH SNAP FASTENERS

Filed March 22, 1932

UNITED STATES PATENT OFFICE

LOUIS BARNETT, OF NEW YORK, N. Y.

IDENTIFICATION DEVICE OR MARKER FOR COOPERATING WITH SNAP FASTENERS

Application filed March 22, 1932. Serial No. 600,545.

This invention relates to identification devices or markers, and more particularly is directed to legend carriers adapted to co-operate with a snap fastener or like releasable closure means.

Among the objects of the invention is to generally improve devices or markers of the character described which shall comprise few and simple parts, which shall be easily and quickly applied to snap fastener devices or like releasable closure means on pocket books, gloves, jackets, clothing, caps and other articles and apparatus, which shall be cheap to manufacture and practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claims.

In the accompanying drawing, in which are shown various possible illustrative embodiments of this invention,

Fig. 1 and Fig. 2 are front and rear elevational views, respectively, of an identification device constructed to embody the invention.

Fig. 3 is a cross-sectional view taken on line 3-3 in Fig. 1.

Fig. 4 is a front elevational view of a modified form of the improved identification device formed with a serrated peripheral edge.

Fig. 5 is a cross-sectional view showing another modification of the improved identification device having a non-abrasive anti-slip peripheral edge.

Fig. 6 is a fragmentary perspective view of a folder or pocketbook showing the improved identification device applied to the snap fastener flap closure means.

Figs. 7 and 8 show fragmentary sectional views of another embodiment of the invention formed with co-operating means for interposing between the male and female mem-

bers of a conventional snap fastener, Fig. 7 showing the parts separated and Fig. 8 the assembly thereof.

Figs. 9 and 10 are views similar to Figs. 7 and 8, respectively except that the identification device here shown is adapted to be interposed between and co-operate with different sizes of snap fastener male and female members to form a permanent part of the releasable closure means.

The invention may be utilized for identification devices or markers for various purposes, and as shown in detail in the drawing, 10 denotes an identification device embodying the invention adapted to cooperate with

a snap fastener or like releasable closure means. The device 10 may be formed of any suitable metallic or non-metallic sheet material but for cheapness may be made of

paper, fibre, rubber, molded compounds, celluloid or other stiff inexpensive material. Said device 10 may be of any desired circular, polyangular or oval shape and as here shown comprises circular disc which has a center opening 10a adapted to fit over the

male member 11 of a conventional snap fastener. Where the male member 11 is a non-resilient or rigid structure, the rim of

the opening 10a of the device 10 may be provided with spaced slits 10b, the diameter of

said opening 10a being made smaller than the diameter of the head 11a of the male member 11 so that the device 10 when applied to said male member can be snapped over the head 11a and retained thereby as

shown in Fig. 6. In the drawing, the snap fastener shown has a rigid member 11, the female member 12 being of resilient construction. It is to be understood that other types of conventional snap fasteners may be used,

such for example as have resilient male members and rigid female members. Devices 10 when used with the latter type of snap fastener may be made with a central opening 10a but requires no slits 10b. With

resilient snap fastener male members (not shown) the devices 10 may be snapped thereon in the well understood manner.

The front or outer surface 10c of the disc structure of the device 10 provides means for

100

imprinting or attaching thereon any suitable legend, advertisement, etc., such as for example, the legend 13 "Owner's name and address on the reverse side", and the rear or inner 5 surface 10d of said disc structure provides means for imprinting or attaching thereon a legend 14 such as the name and address of the owner of the article to which the device 10 is attached.

10 In order that the peripheral rim of the disc structure does not project so as to interfere with the opening or closing snap fastener operation or to detract from the pleasing appearance of the article, said rim 15 may be inwardly flared as at 10e, to bring said peripheral edge in close contact with the surface of the flap 15 of a pocket book 16, shown in Fig. 6. This form of flared disc structure for the device 10 also aids in frictionally retaining the latter engaged with the neck 11b of the male snap fastener member.

If desired, other suitable means may be provided for retaining the device 10 against rotation and consequently eliminating wear 25 at the contact of the device 10 with the surface of the flap 15 or other similar closure. As shown in Fig. 4, such means may comprise serrations 17 of fine teeth formed on the peripheral edge of the disc structure of device 10. Where the material forming the surface of the flap is of a delicate texture instead of providing serrations 17 on the disc structure, the peripheral edge may be provided with an annular flange 18 of non-abrasive anti-slip material such as felt or soft rubber as shown in Fig. 5.

The utility of the invention will now be apparent. The device 10 may be applied to articles to provide a marker, price tag, label 40, or identification device in connection with a conventional snap fastener. As shown in Fig. 6 the identification device 10 is applied to the male member 11 of the snap fastener of the closure flap of the bag so that the front or outer surface 10c is exposed and the inwardly flared peripheral edge 10e contacts with the inner surface of the flap 15. Said flap when retained over the open end of the bag and secured in closed position by engaging the rigid 45 male member 11 with the resilient female member 12 conceals the device 10 from view. The device takes up practically no space, and does not in any manner interfere with the operation of the snap fastener members. The device 10 thus can be utilized as a price tag, label or identification means. When used for the latter purpose, it may have imprinted on the outer surface the legend that the owner's name and address are inscribed on the reverse 50 side. Thus the identification and address of the owner cannot be ascertained until the device 10 is detached. When the device 10 is made of fibre, celluloid or paper, the inner surface 10d may be readily inscribed or imprinted with the name and address of the

owner. The identification device 10 may be readily removed, replaced and changed as required and when provided with means for retaining the same against the rotation such as serrations 17 or the flange 18, the inner surface of the flap 15 or like closure is protected from being worn or otherwise injured due to the contact of the peripheral edge in contact therewith, and the inscription on the inner surface 10d retained in spaced relation from contact with the flap surface thereby avoiding accidental erasure.

70 In Fig. 7, is shown a modified construction of the invention. Here the device 110 may be of similar construction to the disc 10 described above with the exception that instead of providing a central opening 10a, oppositely extending male and female members 21 and 22, respectively, are provided. The male member 21 extends from the front outer surface 110c and the female extends from the rear or inner surface 110d. The male member of the snap fastener closure 111, which may be extended from a closure 115 corresponding to the flap 15 and conventionally engaged with the female member 112, is of the resilient type and is adapted to engage with the rigid female member 22 of the device 110, the resilient male member 21 of the device 110 being adapted to engage with the rigid female member 112. Thus, the device 110 may be interposed between any two conventional snap fastening members 111 and 112 of the type described and provide an identification means which is of more permanent construction than the device 10 described above. In Fig. 17, the conventional snap fastener and the improved device 110 are shown in separated positions and in Fig. 8 the same are shown assembled.

75 In Fig. 9 there is shown another modification of the invention in which the improved device 210 has both the male and female members thereof 121 and 122, respectively, extending from the front or outer surface 210a. The rigid female member 122 is housed within the male portion 121. The rear or inner surface 210d of the device 210 has no projecting portions as in the modification shown in Fig. 7. The resilient male member 211 necessarily is 80 of smaller size than the rigid female member 212, and therefore the device 210 forms a coupling between the male member 211 and the female member 212. This latter construction is distinguished from the assembly shown in Fig. 7 in that the device 210 forms a part of the snap fastening closure.

85 In Fig. 10, the assembly of the separated parties shown in Fig. 9 is shown.

90 It will thus be seen that there is provided a device whereby the several objects of this invention are achieved and which is well adapted to meet the conditions of practical use.

95 As various possible embodiments might be

made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

10 1. The combination with snugly fitting male and female members of a snap fastener, of a legend carrying means inserted between said members, said means comprising a relatively thin and flexible element removably secured to one of said members and overlying the exposed face thereof, the normally covered face of said element being adapted to receive identification matter.

20 2. A combination with snugly fitting male and female members of a snap fastener of a legend carrying means inserted between said members, said means comprising a relatively thin and flexible element having an opening through which said male member extends, said element overlying the male member, the normally covered face of said element being adapted to receive identification matter.

30 3. The combination set forth in claim 1 in which said element is formed with an inwardly flared peripheral edge, as and for the purpose described and specified.

35 4. The combination set forth in claim 1 in which said element is provided with a peripheral edge formed with frictional contact means.

40 5. The combination set forth in claim 1 in which the element comprises a stiff material having a non-abrasive frictional contact surface extending about the periphery thereof.

45 6. The combination with snugly fitting male and female members of a snap fastener, of a legend carrying means inserted between said members, said means comprising a thin disc having an opening formed with a slotted rim portion, said slotted rim portion being adapted to snap over the male member to overlie the exposed face thereof whereby said means may be carried by and removably inserted between said members, the normally covered face of the disc being adapted to receive identification matter.

50 7. The combination with the male and female members of a snap fastener, of a legend carrying means having male and female members of a snap fastener extending from opposite sides thereof for engaging the male and female members to the first mentioned snap fastener members to removably attach said means therebetween.

55 8. A device of the character described comprising a legend carrier disc and engaging means on said disc for attaching said device between the separate parts of a conventional

snap fastener, said disc formed with an inwardly flared peripheral edge said edge terminating in a serration as and for the purpose described and specified.

60 9. The combination of a structure having a flap closure secured by male and female members of a snap fastener, of a thin disc formed with front and rear legend carrier surfaces, and engagement means on said disc removably secured to one of said members, said flap covering and concealing said disc when the latter is retained by the closed snap fastener members.

65 10. The combination with separable male and female members of a snap fastener, of a legend carrier device having male and female members of a snap fastener complementary to said first mentioned members for removably attaching said device between said first mentioned members.

70 11. The combination with the separable male and female members of a conventional snap fastener, of a legend carrier device forming a coupling between said members whereby said device is positioned therebetween.

75 12. A device of the character described comprising a legend carrier disc, and male and female snap fastening members extending from opposite sides of said disc for attaching said device to separable male and female members of a conventional snap fastener.

80 13. A device of the character described comprising a legend carrier disc, and male and female snap fastening members extending from the same side of said disc for attaching said device to separable male and female members of a conventional snap fastener.

85 14. A device of the character described comprising a legend carrier disc, and male and female fastening members extending from opposite sides of said disc for attaching said device to separable male and female members of a conventional snap fastener, said disc formed with flared peripheral edge as and for the purpose described and specified.

90 15. A device of the character described comprising a legend carrier disc, and male and female snap fastening members extending from opposite sides of said disc for attaching said device to separable male and female members for a conventional snap fastener, said disc having a peripheral edge formed with frictional contact means.

95 16. A device of the character described comprising a legend carrier disc, and male and female snap fastening members extending from the same side of said disc for attaching said device to separable male and female members of a conventional snap fastener, said disc formed with flared peripheral edge as and for the purpose described and specified.

100 17. A device of the character described

comprising a legend carrier disc, and male and female snap fastening members extending from the same side of said disc for attaching said device to separable male and female members of a conventional snap fastener, said disc having a peripheral edge formed with frictional contact means.

18. The combination with male and female different sized parts of convention snap fasteners, of a legend carrier having coupling means for attaching the device to said snap fastener parts.

19. A device of the character described comprising a thin disc formed with front and rear legend carrier surfaces, engageable means on said disc for removably attaching the device between male and female members of a snap fastener, and a legend carried on one of said surfaces referring to a legend carried on the other of said surfaces.

In testimony whereof I affix my signature.

LOUIS BARNETT.
